Specification for Design.

Patented Apr. 26, 1921.

Application filed August 11, 1920. Serial No. 402,908. Term of patent 14 years.

To all whom it may concern:

Be it known that I, ERNEST S. McLARN, a citizen of the United States, residing at Glenwood Landing, in the county of Nassau, State of New York, have invented a new, original, and ornamental Design for Desk-Stands for Hand-Telephones, of which the following is a specification, reference being had to the accompanying drawing, forming a part thereof.

The figure is a perspective view of a desk stand for hand telephones, showing my new design.

I claim:

The ornamental design for a desk stand for hand telephones, as shown.

In witness whereof, I hereunto subscribe my name this 31st day of July A. D., 1920.

ERNEST S. McLARN.
